Baldwin Wright.

UNITED STATES PATENT OFFICE.

MATTHEW BAIN DICKIE, OF GLASGOW, SCOTLAND, ASSIGNEE TO NOBEL'S EXPLOSIVES COMPANY, LIMITED, OF GLASGOW, SCOTLAND.

TELEGRAPHIC-CODE CONDENSER.

No. 901,957.

Specification of Letters Patent.

Patented Oct. 27, 1908.

Application filed February 21, 1908. Serial No. 417,213.

To all whom it may concern:

Be it known that I, MATTHEW BAIN DICKIE, mercantile clerk, a subject of the King of Great Britain, residing at Nobel 5 House, 195 West George street, Glasgow, Scotland, have invented new and useful Improvements in Telegraphic-Code Condensers, of which the following is a specification.

The object of this invention is to provide 10 an improved telegraphic code condenser by means of which a very large number, say two hundred thousand pronounceable five letter "words" corresponding to the code numbers from 0 to 199999 may be employed, 15 it being possible to determine the word corresponding to any given number when condensing or the number corresponding to any received word when decoding with the expenditure of very little trouble and time.

20 The condenser is made on the principle of a slide rule and consists of three concentric circular scales.

As the apparatus will be more readily understood by reference to the accompanying 25 drawing it will be described at once with reference thereto.

Figure 1 of the drawing is a plan and Fig. 2 a cross-section of the apparatus.

30 *a* is the largest scale which may be drawn or mounted upon a board or card *b* of any convenient size and shape; the scale is divided into 100 compartments, numbered consecutively from 00 to 99. Each compartment contains besides the two digits of its 35 number two letters corresponding to the number. This scale is also divided into ten divisions, corresponding to the numbers from 00 to 09 (that is from 0 to 9) from 10 to 19, and so on, as is shown in the drawing 40 and what may be called the syllables in the first division are formed of *A* followed by the consonants *B D G K M P R T W Y* (which may be called the first series) in turn. The syllables in the second division are 45 formed of *E* followed by the consonants *C F H L N Q S V X Z* (which may be called the second series) in turn. The syllables in the third division, corresponding to 20 to 29, are formed of *I* followed by the first 50 series; in the fourth, corresponding to 30 to 39, of *O* followed by the second series; in the fifth, corresponding to 40 to 49, of *V* followed by the first series. In the sixth and remaining divisions the syllables are formed 55 of the five vowels in their proper order as

before but preceded by the second, first, second, first and second series in order.

Just within the scale *a* is an intermediate scale *c* also divided into 100 compartments as shown but into five divisions of 20 compartments each. Each compartment contains as in the case of scale *a* a number consisting of two digits (the numbers ranging from 00 to 99 in consecutive order) and a syllable of two letters. In this case all the 60 syllables commence with a vowel those in the first division corresponding to the numbers 00 to 19 begin with *A*; those in the second division corresponding to 20 to 39 with *E* and so on, the consonants of the two series 65 following in each division in alphabetical order *i. e.*, *B C D F G H K L M N P Q R S T V W X Y Z*.

Just within the scale *c* is the innermost scale *d* which essentially consists of only 75 twenty compartments numbered from 0 to 19 and lettered with the whole twenty consonants as above in alphabetical order—these compartments should of course be of the same circular measure as those in scales 80 *a* and *c*, but in order to save trouble in use, it is found convenient to repeat the series of numbers and consonants five times thus filling the entire circumference of the scale *d*. The two scales *c* and *d* are suitably 85 mounted upon a pivot *e* so that they can be readily turned independently of one another relative to scale *a*.

The method of use will be best explained by an illustration.

In transmitting—suppose it is desired to 90 send two sentences or words of which the code numbers are 98804 and 132601—first find the number 04 in scale *a*, then turn scale *c* till the number 38 upon it comes in line 95 with 04 in scale *a* and then turn scale *d* so that any 9 upon it comes in the same line. This gives the word "Neyam." Similarly by turning the scales *c* and *d* till 26 and any 100 13 are in line with 01 we get "Sekad" and adding this to the former word we get "Neyamsekad" which can be cabled for the price of one word.

In decoding a received message for instance "Zuglifupye" we must divide it into 105 two, look out "Li" (which will be found in the eighth division) on scale *a*, turn scale *c* till "Ug" comes in line and then turn scale *d* till one of the Z's upon it comes in line this gives the number 198473. Similarly 110

"Fupye" gives the number 39069. The meaning of these two numbers can then be found in the code book in the usual manner.

It will be seen that by the use of this condenser any two of the natural numbers from 0 up to 199999 in any code book can be condensed into a single ten letter pronounceable word.

What I claim is:—

10. 1. A telegraphic code condenser consisting of concentric circular scales pivotally connected together, each of which is divided into compartments with the compartments in one scale radially in line with the compartments in another scale, each compartment in each scale containing a number and a letter footing on radial lines whereby the number in one compartment of one scale can be brought radially in line with the number in a compartment in another scale and in like manner the letter in one scale can be brought radially in line with the letter in another scale.
15. 2. A telegraphic code condenser consisting of a circular scale having a number of

compartments each containing a number of two digits and a syllable formed of a vowel and a consonant, an intermediate scale also having a number of compartments each containing a number of two digits and a syllable formed of a vowel and a consonant and an inner scale also having a number of compartments each containing a number and a consonant.

3. A telegraphic code condenser consisting of a circular scale with numerous compartments each containing a number of two digits and a syllable of two letters, the compartments being divided into divisions according to the vowels employed in them an intermediate scale also divided into the same number of compartments each containing a number of two digits and a syllable of two letters and an inner scale with numerous compartments substantially as described each containing a number and a letter.

MATTHEW BAIN DICKIE.
